Primary Examiner — Elizabeth Albert(74) *Attorney, Agent, or Firm* — Stevens & Showalter LLP(57) **CLAIM**

An ornamental design for a writing instrument, as shown and described.

DESCRIPTION

FIG. 1 is a front view of my design;

FIG. 2 is a back view thereof;

FIG. 3 is a side view taken from the left side thereof;

FIG. 4 is a side view taken from the right side thereof;

FIG. 5 is a top view thereof (enlarged for clarity);

FIG. 6 is a bottom view thereof (enlarged for clarity); and,

FIG. 7 is an enlarged side view of the top portion of FIG. 4, to enhance the details shown in FIG. 4.

The broken line on the bottom of the enlarged side view of FIG. 7 is shown for environmental purposes only and forms no part of the claimed design.

1 Claim, 3 Drawing Sheets# US D651,246 S
